(57) **CLAIM**

The ornamental design for an electrical connector, as shown and described.

DESCRIPTION

FIG. 1 is a front elevational view of an electrical connector showing our new design;
FIG. 2 is a top plan view thereof;
FIG. 3 is a right side elevational view thereof;
FIG. 4 is a left side elevational view thereof;
FIG. 5 is a rear elevational view thereof;
FIG. 6 is a bottom plan view thereof;
FIG. 7 is a front and top perspective view thereof;
FIG. 8 is a front and bottom perspective view thereof;
FIG. 9 is a rear and top perspective view thereof; and,
FIG. 10 is a rear and bottom perspective view thereof.
The broken line shown in the figure drawings is included for the purpose of illustrating unclaimed environment and forms no part of the claimed design.
